(57) **CLAIM**

The ornamental design for a motor vehicle, toy replica, and/or other replica, as shown and described.

DESCRIPTION

FIG. 1 is a left, front perspective view of a motor vehicle, toy replica, and/or other replica showing our new design;

FIG. 2 is a left, rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

The broken lines in the drawings illustrate environmental subject matter only and form no part of the claimed design.
